UNITED STATES PATENT OFFICE.

RAYMOND B. GLIDDEN, OF KEWANEE, ILLINOIS, ASSIGNOR TO IDEAL MANUFACTURING COMPANY, OF KEWANEE, ILLINOIS, A PARTNERSHIP COMPOSED OF B. E. BAKER, W. D. GLIDDEN, AND R. B. GLIDDEN.

BOTTLE-CAPPER.

1,358,145.

Specification of Letters Patent. Patented Nov. 9, 1920.

Application filed September 29, 1919. Serial No. 327,340.

To all whom it may concern:

Be it known that I, RAYMOND B. GLIDDEN, a citizen of the United States, residing at Kewanee, in the county of Henry and 5 State of Illinois, have invented certain new and useful Improvements in Bottle-Cappers, of which the following is a specification.

My invention relates to bottle-capping appliances such as are adapted to seal bottles 10 with sheet-metal caps containing disks of cork or other suitable material by bending or crimping the edges of the cap or closure over the end of the bottle. Its leading object is the provision of a device of this type 15 capable of efficiently performing such work, which is simple in structure and economical to produce, at the same time being of such form and having its operative parts so associated or connected together that the appliance is unlikely to be damaged or broken 20 in service.

In order that those skilled in this art may become acquainted with the structural characteristics of a desirable embodiment of the 25 invention and may have a full understanding of its functional capabilities, I have illustrated a preferred embodiment of the invention in the accompanying drawing forming a part of this specification and 30 throughout the views of which like reference characters refer to the same parts.

In this drawing:

Figure 1 is a side view of the device attached to a wall, shown in association with a 35 portion of a bottle;

Fig. 2 is a plan view of the apparatus of Fig. 1 with a portion of the handle broken away; and

Fig. 3 is a section on line 3—3 of Fig. 1 40 with the bottle omitted.

Referring to these drawings, it will be seen that the device comprises a bracket-member 10 adapted to be fastened to a wall or other suitable support by means of screws 45 11, 11, extended through apertures 12, 12, of the main body of such element which is adapted to rest flatwise against the face of the wall as shown in Fig. 1. At its bottom end such bracket is provided with an integral projection 13 equipped with a pair of curved arms 14, 14, the faces of which 50 unitedly or conjointly form a recess or socket adapted to receive a portion of the neck of

the bottle 15, whereby the latter is adapted to be easily and quickly centered beneath the 55 reciprocatory capper ready for the action of such element on the cap of the bottle.

This projection 13 is provided with a vertical hole 16 therethrough into which is tightly fitted and firmly held the lower end 60 of an upstanding cylindrical guide-rod 17 on which slides an apertured vertical rib 18 of a hollow reciprocating or sliding capper 19, which is shaped internally to perform the capping operation with facility and despatch. Upstanding from such capper there is an apertured lug 20 the upper portion of 65 which is received in a cavity or socket 21 in the lower face of a lever handle 22, the parts 20 and 22 having a hinge connection by reason of a hinge bolt 23 which extends horizontally through the perforation of the lug 20 and the aligned apertures in the side-walls 70 of the cavity 21.

The upper end portion of the bracket 10 75 is provided with two forwardly-extended ears 24, 24, apertured in register or alignment for the reception of a fulcrum-bolt 25 extending through an elongated longitudinally-disposed slot in the end portion of the 80 handle lever which is positioned between the two supporting ears 24, 24.

The appliance illustrated and described operates substantially as follows:

With the lever handle 22 elevated as 85 shown in Fig. 1, with the capper 19 in raised position and the fulcrum pin or bolt 25 in the inner portion of the slot of the lever, the bottle 15 and its cap are inserted in place, being guided to and held in proper position 90 or register with the reciprocatory capper by curved arms 14, 14. Thereupon, the capper is pressed downwardly by depression of the handle 22, the capper sliding in a straight line by reason of its association with the 95 guide-post or standard 17 and being prevented from turning on such post because of its connection with the handle and the pivotal connection of the latter with the bracket ears 24. Such depression of the capper 100 causes its inner surface to engage the cap and crimp its edge over the mouth of the bottle as is shown in Fig. 1. The cap affixing operation having been thus completed, the capper is again raised by the lifting of 105 the handle and the capped bottle removed

so that the appliance is again ready for the reception of an uncapped bottle, as explained above.

It will be understood that because of the loose fulcrum connection of the lever or handle with the bracket the capper is permitted to have a straight line up and down movement as determined by its sliding connection with the fixed post or standard 17, 5 the fulcrum connection automatically accommodating itself as is required to permit such straight-line motion of the capper. Inasmuch as the lever or handle cannot turn or shift sidewise on its fulcrum-bolt and like displacement of the capper relatively to the handle is prevented, the capper cannot turn about the guide-rod and is compelled to slide in a rectilinear path.

Those skilled in this art will appreciate 20 that the invention is not necessarily limited to the precise and exact features of construction of this particular embodiment thereof and that many minor mechanical changes 25 may be incorporated in the structure without departure from the substance and essence of the invention and without the sacrifice of any of its substantial benefits and advantages.

I claim:

30 1. In a bottle-capping appliance of the character described, the combination of a supporting bracket adapted to be fastened to a wall having a horizontal projection near

its lower end with horizontal curved arms 35 unitedly forming a recess adapted to accommodate and center the neck of the bottle to be capped and having a pair of spaced ears near its top end apertured in alignment, an upright post secured to and upstanding from said bottom projection, a 40 sliding capper having an apertured rib receiving and guided in its reciprocation by said post and an upwardly-extended perforated lug, a handle lever having a slotted end portion, a fulcrum-pin accommodated 45 in the apertures of said upper ears and extending through the slot of said handle lever, said handle having a cavity in its bottom face receiving said capper lug, and a hinge-pin extended through apertures in 50 the side-walls of said handle cavity and the perforation of said capper lug, substantially as described.

2. In a bottle-capping appliance of the character described, the combination of a 55 supporting bracket adapted to be fastened to a wall having a horizontal projection near its lower end with bottle centering means, an upright post secured to and upstanding from said projection, a capper having a sliding connection with said post, and an operating-lever having a sliding fulcrum connection with said bracket and a hinge connection with said capper, substantially as described.

RAYMOND B. GLIDDEN.
